UNITED STATES PATENT OFFICE.

WENDELL P. WATKINS, OF IOWA CITY, IOWA.

BALE AND PACKAGE TIE.

No. 923,222.

Specification of Letters Patent.

Patented June 1, 1909.

Application filed February 15, 1908. Serial No. 416,129.

To all whom it may concern:

Be it known that I, WENDELL P. WATKINS, a citizen of the United States, residing at Iowa City, in the county of Johnson and 5 State of Iowa, have invented certain new and useful Improvements in Bale and Package Ties, of which the following is a specification.

My invention relates to an improvement in bale and package ties, and the object is to 10 provide a fastening means for tying bundles of letters, or any other article or articles. It has been found to be particularly adapted to letters, as letters in the ordinary manner of tying, have a tendency to creep or slip at the 15 ends, and are not held firmly in place, and by my improved device I have provided means whereby a package or bundle of letters can be tied very quickly, and in a great deal less time than the ordinary manner.

20 The invention relates to certain other novel features of construction and combinations of parts which will be hereinafter described and pointed out in the claim.

In the accompanying drawings:—Figure 25 1 is a top plan view. Fig. 2 is a longitudinal sectional view. Fig. 3 is a perspective view showing the invention applied to a package.

A, represents a metal plate of any suitable material having a binding post 1 struck up 30 from the center thereof. This post is preferably in an upright position and slightly curved back toward the body of the plate.

A tie post 2 is struck up from the center and bent over, leaving a small opening or space 35 between the plate and post for the reception of the cord 3. The slot 4 formed in the plate by the binding post and tie post being struck out of the plate, is preferably tapering or in other words the width of the binding post 1 is 40 preferably smaller than the width of the tie post.

An opening 5 is formed in one end of the plate for the cord 3 which passes over the ends and around the envelop, and is clasped 45 around the binding post 1, and then around the sides of the envelop, coming up on the other side and passing again around the bind-

ing post, and thence around the tie post, and then back around the binding post, and then again around the tie post. Of course 50 it is not necessary that the cord pass so many times around the tie post, as the opening formed between the tie post and the plate is made tapering and smaller at the inner end, so that the cord as it passes into the slot will 55 receive a binding or gripping action as it is forced into the opening. So in reality, it is only necessary to pass the cord around the binding post twice and under the tie post once when the package will be securely tied. 60 This tying operation can be done very quickly as the package can be grasped or held in the left hand, and with the thumb pressing or holding the tie plate A on the package, the cord can be quickly passed 65 around the package until it is tied.

It is evident that more or less slight changes might be resorted to in the form and arrangement of the several parts described without departing from the spirit and scope 70 of my invention, and hence I do not wish to limit myself to the exact construction herein set forth, but:—

Having fully described my invention, what I claim as new and desire to secure by Letters Patent, is:—

As an article of manufacture, a bale or package tie, comprising a plate having a slot formed therein and the metal cut from the plate to form the slot left integral with the 80 plate at its ends and divided at or near the center and bent backwardly in opposite directions whereby to form two independent integral tie posts, one extending at an angle from the plate and the other extending parallel with the plate, adapted to have wound there around the flexible device used in securing the package.

In testimony whereof I affix my signature in presence of two witnesses.

WENDELL P. WATKINS.
